UNITED STATES PATENT OFFICE.

GUY B. COLLIER, OF KINDERHOOK, NEW YORK.

GAS-LIGHTING APPARATUS.

1,262,753.

Specification of Letters Patent. Patented Apr. 16, 1918.

Application filed December 27, 1916. Serial No. 139,106.

To all whom it may concern:

Be it known that I, GUY B. COLLIER, a citizen of the United States, residing at Kinderhook, in the county of Columbia and 5 State of New York, have invented certain new and useful Improvements in Gas-Lighting Apparatus; and I do hereby declare the following to be a full, clear, and exact description of the invention, such as will enable others skilled in the art to which it 10 pertains to make and use the same.

The present invention relates to gas lighting apparatus and more particularly to apparatus of this type which automatically 15 lights and extinguishes the main gas burner at predetermined intervals.

It is the object of the present invention to reorganize and improve apparatus of this character whereby the apparatus is rendered 20 more efficient and certain in its operation.

With this object in view the various features of the invention consist in certain novel features of construction, combinations and arrangements of parts hereinafter described 25 and claimed, the advantages of which will be obvious to those skilled in the art from the following description.

In the preferred form of the invention Figure 1 represents a front elevation of the 30 improved apparatus; Fig. 2 is a side elevation partly in section of the apparatus attached to an ordinary type of lamp; and Fig. 3 is a detail illustrating upon an enlarged scale certain important features of 35 construction.

The construction shown in the illustrated embodiment of the invention comprises essentially a clock mechanism and a timing mechanism operated thereby for opening 40 and closing a gas valve at predetermined intervals. The clock mechanism and timing mechanism are conveniently combined to form a single unitary construction which operates a suitable type of gas valve to cause 45 the lighting and extinguishing of the gas at predetermined intervals and without manual intervention. The apparatus is conveniently inclosed in a casing 10 supported by a main gas pipe, indicated at 11. A tubular arm 12 50 extends horizontally from a casing secured to the gas pipe and is provided with a threaded end 13 which is received within a boss 14 formed upon the upper end of the casing 10, as shown clearly in Fig. 2. The

gas pipe is inclosed within a hollow post 55 16 in the usual manner and supports the base 17 of the lamp. The specific form of gas valve is not illustrated herein but may be the same as that shown and described in the patent to Collier No. 1,138,265, March 60 30, 1915. This valve is operated by a rock shaft 18 extending through the hollow arm 12 and provided upon its opposite end with an operating arm 19.

In order to prevent the escape of gas from 65 the main gas passage through the hollow arm into the casing 10 the rock shaft 18 is provided with a series of washers 20 of felt or other similar material which surround the rock shaft within the arm 12. Lubrication is supplied to the rock shaft through an oil duct 22 formed in the arm 12 and communicating with the washers. The provision of a plurality of washers received within the arm and fitting the rock shaft serves 70 75 two functions. The washers act as a container and oil reservoir for maintaining the shaft lubricated and at the same time form an effectual seal for preventing the escape of gas from the gas passage into the casing 10. 80 If the gas should by any chance leak through some of the washers the oil duct will act as a vent therefor as it offers a passage for the escape of gas which is shorter than the passage into the casing. 85

The mechanism as a whole is supported upon a back plate 25 secured to the casing 10, as shown clearly in Fig. 2. The clock mechanism may be of the usual type provided with front and back plates 27 and 28, 90 respectively, which are separated by standards 29 and are secured to the back plate 25 through arms 30.

The timing mechanism is constructed and arranged to open and close the gas valve by 95 moving the rock shaft in opposite directions. To this end an opening member and a closing member are employed and are arranged to operate the gas valve through the rock shaft at predetermined intervals. In 100 the illustrated embodiment of the invention these members consist of a pair of dogs carried by two rotating dials which are geared together to rotate in opposite directions and are conveniently driven from the large gear 105 35 of the clock mechanism. It may be mentioned that this is a usual gear incident to clock mechanisms of this type so that a com-

mercial clock mechanism may be employed without modification. Referring to Fig. 1 of the drawings it will be noted that a pair of dials 36 and 37 are provided and are 5 journaled upon a plate 39 secured to the back plate 25 through a plurality of standards 40. The dials 36 and 37 are provided, respectively, with gears 41 and 42 having the same number of teeth and meshing with 10 one another to cause the dials to rotate in opposite directions at the same speed. The gear 42 is driven from the clock gear 35 through a small gear 43, mounted upon a shaft 44 and meshing with the gear 35 and a 15 pinion 45 secured to the shaft 44 and meshing with the gear 42. The intermediate gears are arranged to rotate the large gears 41 and 42 once in each twenty-four hours.

In order to permit an adjustment of the 20 dials relative to the clock mechanism, means are conveniently provided for permitting a relative rotation of the gear 43 and shaft 44. To this end the gear 43 is frictionally locked to the shaft 44 by a spring 46 which 25 maintains one face of the gear in yielding engagement with a shoulder 47 formed integral with the shaft. The opposite end of the spring engages with a collar 48 secured by a pin 49 extending through the shaft 44. 30 With this construction the shaft is normally rotated with the pinion 43 but may be adjusted relative thereto by engaging the squared end 50 of the shaft with a suitably shaped key.

35 The valve operating shaft is operatively connected with the opening and closing dials through two levers which may be referred to, respectively, as an actuating lever and a valve lever. The actuating lever is oper- 40 ated at predetermined intervals by the opening and closing dogs carried by the dials and in turn serves to move the valve lever from one operative position to another in which the gas valve is either opened or 45 closed. After the valve lever has been moved to one of two operative positions to open or close the gas valve it serves to retain the gas valve in this position until again moved by the actuating lever. According to 50 this construction a valve lever 60 is fulcrumed upon a shaft 51 extending from the back plate 25 and an actuating lever 53 is fulcrumed upon a shaft 54 secured to the back plate, as shown clearly in Figs. 2 and 3 55 of the drawings. The valve lever is arranged to be rocked into one of two inclined positions by the actuating lever and is retained in either inclined position by a weight 55 secured to the end of the valve lever, as 60 shown clearly in Fig. 2 of the drawings. The valve lever is provided with an enlarged portion adjacent the lower end having a slot 56 formed therein and serving to oper- 65 atively connect the valve lever with the actuating lever 53 and the arm 19. To this end

the actuating lever is provided with a laterally extending stud 57 projecting within the slot and arranged to traverse between opposite ends of the slot, as indicated in Fig. 3 of the drawings, and the arm 19 is provided with a stud 61 received within a branch 62 of the slot extending lengthwise of the lever 60. With this construction the movement of the actuating lever from the position shown in Fig. 3 to a position in which the actuating lever is inclined in the opposite direction causes an abrupt movement of the valve lever 60 in a corresponding direction and rocks the arm 19 sufficiently to open the valve. The movements of the valve lever are limited when the lever is disconnected from the arm 19 and the operative position of the lever is determined when the main gas valve is opened by a stud 65 projecting from the back plate 25 and received within a depression 66 formed in the slot 56, as shown clearly in Fig. 3. In order to insure that the gas valve may be completely closed the stud 65 is not normally arranged to engage with the depression 66 when the valve lever 60 is located in the inclined position opposite to that shown in Fig. 3.

The actuating lever 53 is intermittently moved in opposite directions by an opening member 68 rotating with the dial 37 and a closing member 69 rotating with the dial 36. Each member comprises an arm 70, as shown clearly in Fig. 3, extending from the respective dial shaft and having its end provided with a lateral stud 71 adapted to engage 100 with one of the wings 72 and 73 extending from the actuating lever 53 adjacent the fulcrum, as shown clearly in Fig. 3. It will be observed that the rotation of the dial 37 in the direction of the arrow causes the stud 71 to engage beneath the wing 72 of the actuating lever, tipping the lever gradually about the fulcrum 54. In a like manner the rotation of the dial 36 in the opposite direction causes the closing member to engage beneath the wing 73 of the actuating lever, tipping it in the opposite direction.

The actuating lever is retained in an inclined position and the movements from one inclined position to another are aided by a 115 release and accelerating lever 75 fulcrumed at 76 upon the back plate and having its free end engaging with a stud 77 projecting from the actuating lever. It will be noted from an inspection of Fig. 3 that the end of the arm in engagement with the stud is provided with oppositely inclined faces 78 and 79 which are maintained in engagement with the stud by a coiled spring 80 surrounding the fulcrum 76 and serving to normally depress the lever 75. With this construction the lever 75 serves to retain the actuating lever in either inclined position to which it is moved and to aid in moving the lever to this position after it has passed the vertical. 120 125 130

In order to insure the operation of the valve lever by the actuating lever the latter is provided with a weight 82 on the outer end.

According to the above construction one 5 of the wings 72 or 73 of the actuating lever is first engaged by a rotating stud which slowly rocks the lever from an inclined to a substantially vertical position. At this point the stud 77 passes from one inclined 10 face to another of the controlling arm 75 which causes the controlling arm to impart an abrupt movement to the actuating lever, aided by the weight 82. This continues until the stud 57 has engaged with the end of the 15 slot 56 and moved the valve lever from one inclined position to another.

It will be observed that both the dials 36 and 37 are marked to indicate hours and that each dial is provided with a pointer 85 moving therewith and a stationary pointer 86 mounted above the dial. The stationary pointer, when read in connection with the dial, shows the actual time, as indicated by the dial, and the movable pointer is connected to the corresponding opening or closing member and indicates the position of this member and the time at which the gas valve will be opened or closed. For example, upon observing Fig. 1 of the drawings it will be 20 noted that both of the dials indicate in connection with the stationary pointers that the time is three-thirty a. m. The pointer 85 in connection with the dial 36 indicates that the gas valve was closed at one-thirty a. m. and 25 the pointer 85, in connection with the dial 37, indicates that the valve will be opened at the following seven-thirty p. m.

In order to set the movable pointers relative to the dials to vary the opening or 30 closing of the main gas valve each pointer 85 is connected to a corresponding arm 70 through an arbor 90 having a squared end to receive a key, as shown clearly in Fig. 1. The dial is loosely received upon the arbor 45 and is provided with a hub journaled in the front plate 25. The dial is normally secured to the arbor through a cup shaped spring 50 washer 92 which serves to clamp the arm 70 and the hub of the dial together. This construction normally causes the arm 70, pointer 85 and dial to rotate together but permits the pointer and arm to be adjusted relative to the dial when desired.

While it is preferred to employ the specific construction and arrangement of parts 55 shown and described, it will be understood that this construction and arrangement is not essential except so far as specified in

the claims, and may be changed or modified without departing from the broader features 60 of the invention.

The invention having been described, what is claimed is:

1. A gas lighting apparatus, comprising a clock mechanism, an actuating lever, connections between the clock mechanism and actuating lever for moving the actuating lever in opposite directions at predetermined intervals, a valve lever pivoted at one end and having a slot formed therein adjacent 70 the fulcrum, a stud projecting from the actuating lever into the slot, a valve shaft, an arm secured to the valve shaft and a stud projecting from the arm and received in a recess formed in the valve lever intersecting 75 the slot to cause the movements of the valve lever to operate the valve shaft.

2. A gas lighting apparatus, comprising a pair of oppositely rotating dials, a clock mechanism for rotating the dials at a predetermined rate, an arm associated with each dial and rotating therewith, an actuating lever fulcrumed at one end and having a pair of oppositely extending wings, a stud projecting from each arm and constructed 85 and arranged to engage with one of the wings to cause the rotation of the arms to rock the actuating lever at predetermined intervals, a valve shaft, and connections between the valve shaft and actuating lever. 90

3. A gas lighting apparatus, having in combination, a tubular support, a valve shaft journaled in the support, a plurality of yielding washers surrounding the shaft within the support and an oil passage 95 extending through the support into communication with the washers to permit lubrication of the shaft and the escape of gas therethrough, a clock mechanism, and operative connections between the clock mechanism 100 and valve shaft for rocking the valve shaft at predetermined intervals.

4. A gas lighting apparatus, having in combination, a clock mechanism including a large gear, a shaft having an annular shoulder formed thereon, a gear supported upon the shaft and meshing with the large gear, means for yieldingly maintaining the face of the gear in engagement with the corresponding face of the shoulder to frictionally clamp 110 the gear to the shaft, a rotating dial, connections between the shaft and dial, a valve shaft, and operative connections between the dial and valve shaft for rocking the valve shaft at predetermined intervals.

GUY B. COLLIER.
